WINDOW SHADE ROLLER AND CURTAIN BRACKET

Filed Feb. 28, 1929

William E. Sorensen

UNITED STATES PATENT OFFICE

WILLIAM EARL SOUDERS, OF CINCINNATI, OHIO

WINDOW SHADE ROLLER AND CURTAIN BRACKET

Application filed February 28, 1929. Serial No. 343,511.

This invention relates to a window shade roller and curtain bracket which may be clamped to a window frame instead of nailed or screwed thereto.

5 An object of the invention is to provide a device for the purposes stated, which may be adjusted to accommodate window frames of various sizes and which may at the same time be independently adjusted to support shade rollers of various lengths.

Another object is to construct a device of the above character which will not mar the finish of the window frame to which it is attached.

15 Other objects will manifest themselves as the description proceeds with reference to the accompanying drawings, in which:

Fig. 1 is a front elevational view of the device showing the manner of application to a 20 window frame.

Fig. 2 is a side elevational view of an adjustable clamp member forming part of my invention.

Fig. 3 is a perspective view of a detachable 25 mounting plate for drapery or curtain support brackets.

Fig. 4 is a perspective view of one type of drapery or curtain support bracket that may be used in conjunction with the device of my 30 invention.

Fig. 5 is a partial view of a shade roller support forming a detail of my invention.

Fig. 6 is a perspective view taken on line 6-6 of Fig. 2.

35 The device of my invention consists generally of a clamp member 7 and a substantially flat shiftable plate 8 mounted thereon. The plate 8 is provided with a forwardly extending shade roller support 9 (Fig. 5) provided 40 with the usual slot 10 for receiving one end of the well known spring shade roller. The devices of my invention are of course used in pairs, and the device on the opposite side of the window frame is identical with that 45 shown in Fig. 1 with the exception that the corresponding support 9 is provided with a perforation instead of a slot 10, for receiving the opposite end of the shade roller.

A pair of vertical guides 12 form, with the 50 body portion of plate 8, a way 13 for receiving

the tongue 14 of a mounting plate 15 for drapery or curtain support brackets. Dashed lines 16 in Fig. 1 indicate the manner in which said plate is supported in the way by means of the tongue 14. Spaced perforations 17 are provided in the mounting plate whereby the curtain or drapery support bracket 18 may be attached thereto by screws or other suitable securing means extending through perforations 19 in the bracket 18. Brackets 18 are procurable on the market and form no part of my invention, they being merely a known means for supporting curtain or drapery rods extending transversely of the window frame. It will be understood that additional perforations 17 may be formed in the mounting plate 17 for the accommodation of other types of brackets such as 18.

The adjustable clamp member 7 is of two lengths of sheet metal 20 and 21. Member 21 is provided at one end 22 with a socket 23, which is preferably of triangular shape, and which is provided with an inwardly turned claw or hook 24. Said claw is formed at the outer extremity of the juncture of the two triangular faces 25 and 26 forming the socket 23. Stud bolts 27 are provided on the member 21, the heads 28 of said bolts being anchored to the member by welding, peening or the like. The said bolts are equally spaced from one another and are adapted to cooperate with equally spaced perforations 29 in the member 20 for retaining the members 20 and 21 in adjusted positions relative to one another. Suitable nuts 30 are provided for use on the bolts 27. It should be clear from the disclosure in Fig. 2 that longitudinal adjustment of members 20 and 21 may be had by inserting the bolts of member 21 in different perforations 29 of member 22.

The free end 31 of member 20 is bent upon itself as at 32 to form an extension or arm 33 substantially at right angles to the body of member 20. This arm or extension is provided with a threaded bore 34 for receiving a screw or threaded member 35 on one end of which is a head 36, and on the opposite end of which is rotatably mounted a triangular abutment means or block 37. Screw 35 extends toward socket 23 in parallelism with

clamp members 20 and 21. The abutment block 37 is rotatably mounted upon the screw in any suitable manner such by inserting the unthreaded end 38 thereof in an enlarged bore 5 39 in the block, and then peening the end 38 as shown. A rivet 40 may secure the free end 31 of member 20 to the body portion thereof. It should be noted that the vertex 41 of the block 37 points toward the socket 23 on clamp 10 member 21.

The clamp member proper is mounted upon a window frame 42 diagonally thereof by first placing the socket over the outer corner 43 and then placing the block 37 in the notch 44 15 formed by the angularly disposed window frame members, the screw 35 being then tightened for holding the device securely in position. After thus securing the clamp to the frame, the nuts 30 holding plate 8 to the clamp member may be loosened, whereupon the said plate may be adjusted laterally relative to the clamp member for varying the distance between the shade roller brackets 9 on the opposite sides of the window frame. The 20 curtain and drapery mounting plate 15 of course is movable with the plate 8. Said lateral movement of the plate 8 is made possible by providing the plate with longitudinal parallel slots 45 each of which is adapted to 25 freely receive therein one of the stud bolts 27. It will be observed that vertical adjustment of the plate 8 may be had, if desired, by removing nuts 30 and placing the plate with the slots 45 in registry with different studs 27. 30 An extra bolt may be provided for the lowermost perforation 29 when it is desired to dispose plate 8 in the lowermost position.

Felt padding or the like may be glued or 40 otherwise attached at the necessary places to preclude contact of the metal parts with the woodwork.

It is to be understood that various changes may be made in the structural details of the device, within the scope of the claims, without departing from the spirit of the invention.

What I claim is:

1. In a device of the class described the combination of a clamp means comprising a 50 socket on one end and an abutment means on the opposite end thereof for attachment of the clamp means diagonally to a frame, a shiftable plate having support means thereon for supporting a shade roller, securing means on the clamp means for holding the plate in adjusted positions upon the clamp means, a way on the plate, a mounting plate for curtain and drapery support brackets, and means on said mounting plate receivable 55 in the way for support of the mounting plate upon the shiftable plate.

2. In a device of the class described the combination of a clamp means for attachment to a window frame, a plate carried by 60 the clamp means, a shade roller support and

a guide means on the plate, said guide means being adapted to removably receive a curtain and drapery support means, and means for adjusting the plate upon the clamp means both vertically and horizontally of the window frame.

3. In a device of the class described the combination of a clamp means comprising a clamp member having a plurality of perforations, an adjustable abutment means on one end thereof, a second clamp member, a cooperative abutment means on the second clamp member, extending securing means on the second clamp member for reception in the perforations of the first clamp member, a plate having an elongated opening therein for receiving any one of the extending securing means, said plate being thereby adjustable relative to the clamp means, and means on the plate for supporting drapery and curtain support means and one end of a shade roller.

4. In a device of the class described the combination with a support means of a plate having formed therein parallel elongated openings, a shade roller support on the plate, guide means on the plate extending transversely thereof, a removable curtain and drapery support mounting plate, means on said mounting plate for cooperation with the guide means for removable mounting of the second mentioned plate upon the first mentioned plate, and means associated with the support means and receivable in the elongated openings of the first mentioned plate for adjustable mounting thereof upon the support means.

5. In a device of the class described the combination of a clamp member having perforations therein spaced from one another, an adjustable block on said member, a second member having a socket on an end thereof, extending securing means on the second member spaced for reception in the perforations of the first member, the number of perforations exceeding the number of securing means whereby the securing means may be disposed in various of the perforations for varying the distance between the block of the first member and the socket of the second member, a shiftable plate having a plurality of elongated parallel perforations therein spaced to receive certain of the securing means for independent horizontal and vertical adjustment of the plate and for maintaining the plate at a predetermined angle relative to the said first and second members, and means on the shiftable plate for supporting a shade roller and a curtain rod.

6. In a device of the class described the combination of a clamp member having perforations therein spaced from one another, an adjustable block on said member, a second member having a socket on an end thereof, extending securing means on the second mem-

ber spaced for reception in the perforations of the first member, the number of perforations exceeding the number of securing means whereby the securing means may be disposed in various of the perforations for varying the distance between the block of the first member and the socket of the second member, a shiftable plate having a plurality of elongated parallel perforations therein spaced to receive certain of the securing means for horizontal adjustment of the plate and for maintaining the plate at a predetermined angle relative to the said first and second members, a shade roller bracket and vertical 10 guide means on the plate, and a removable curtain bracket having a tongue for reception by the guide means.

7. In a device of the class described the combination of a support member adapted for disposition diagonally of a window frame member, a plurality of securing means on the support member, and a plate having an elongated slot cooperating with any one of the securing means whereby the plate may be independently adjustable horizontally and vertically relative to the window frame, a vertical guide means on the plate, and a curtain bracket support having a tongue for cooperation with the guide means for removably mounting the curtain bracket support upon the plate.

In testimony whereof, I have hereunto subscribed my name this 26th day of February, 1929.

35 WILLIAM EARL SOUDERS.
